AU 291 EX

OR D 13,970

DESIGN FOR A BURIAL-CASKET.

Design No. 13,970, dated June 5, 1883.

UNITED STATES PATENT OFFICE.

THOMAS M. TAYLOR, OF MOUNT VERNON, NEW YORK.

DESIGN FOR A BURIAL-CASKET.

SPECIFICATION forming part of Design No. 13,970, dated June 5, 1883.

Application filed March 26, 1883. Term of patent 7 years.

To all whom it may concern:

Be it known that I, THOMAS M. TAYLOR, a citizen of the United States, residing at Mount Vernon, in the county of Westchester and State of New York, have invented a new and original Design for Burial-Caskets, of which the following is a specification, reference being had to the accompanying drawing, forming part thereof.

10 This design has for its object to provide a novel burial-casket; and the features constituting the design will be hereinafter described, and pointed out in the claim, reference being had to the accompanying drawing, which represents a perspective view of the casket.

15 In the drawing, the letter A designates the body of my casket, in each corner of which is formed a niche, B, which contains a column, a, in full relief. This column rests upon a block, b, with an oblique face and offset, b². The block b rises above the bottom of the niche B. To the bottom edge of the body A is secured a molding, O, which extends from one of the blocks b to the other, and which consists of 20 two oblique members, e f, and a vertical member, g. The oblique member e overhangs the member f. On the upper part of the body A is secured a rectangular strip, g', which extends round the corners above the niches B, so as to impart to the entablature of said 25 niches an ornamental appearance.

The top or cover C of my casket is constructed of side pieces, h, corner-pieces i, and a top, j. The side pieces, h, have oblique faces h' and outwardly-projecting flanges h². The faces 35 are ornamented by raised panels h³. The corner-pieces rise above the side pieces, and they have oblique faces and flanges i², which project outward beyond the flanges h². The top j rests upon the side pieces, and it rises above 40 the upper edges of the corner-pieces.

What I claim as new, and desire to secure by Letters Patent, is—

The design for a burial-casket, consisting of the body A, having the niches B, the corner-blocks b, having oblique faces and offsets b², the column a, the molding O, composed of the oblique member f and overhanging member e, the continuous strip g', and the cover C, composed of the top j, oblique faces h', raised panels h³, flange h², and corner-pieces i, having oblique faces and flanges i², substantially as shown.

In testimony whereof I have hereunto set my hand and seal in the presence of two subscribers.

THOS. M. TAYLOR. [L. S.]
